ATTORNEY

UNITED STATES PATENT OFFICE.

JOHN E. FINNEY, OF SPOKANE, WASHINGTON.

PLIER-WRENCH.

1,085,198.

Specification of Letters Patent.

Patented Jan. 27, 1914.

Application filed March 10, 1913. Serial No. 753,394.

To all whom it may concern:

Be it known that I, JOHN E. FINNEY, a citizen of the United States, residing at

Spokane, in the county of Spokane and 5 State of Washington, have invented certain new and useful Improvements in Plier-Wrenches; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in plier wrenches, comprising essentially a fixed and a sliding jaw, having lever and ratchet mechanism for operating 20 the movable jaw, means being provided to limit the outer throw of the movable jaw.

My invention comprises various details of construction and combinations and arrangements of parts which will be herein- 25 after fully described, shown in the accompanying drawings and then specifically defined in the appended claim.

My invention is illustrated in the accompanying drawings, in which:—

30 Figure 1 is a side elevation of a wrench made in accordance with my invention, and Fig. 2 is an enlarged detail sectional view showing one handle in position to allow the sliding jaw to move without interference 35 with the teeth upon the handle.

Reference now being had to the details of the drawings by letter, A designates a fixed jaw having a slot B formed therein and a handle D. The movable jaw is design- 40 nated by letter C and is provided with a laterally extending shank portion E movable within said slot transversely and is provided with ratchet teeth F upon the under edge thereof. At the end of said 45 shank portion, farthest from the jaw which is integral therewith, a tooth F' projects beyond the series of teeth and serves to co-operate with a shoulder K formed upon the lever N at one end of the series of ratchet 50 teeth O formed thereon. The lever N is

pivotaly mounted upon a pin R passed through registering apertures in the walls of said slot.

By the provision of a wrench made in accordance with my invention, it will be noted 55 that, when the handle is swung to the position shown in dotted lines, the sliding jaw may be moved to its limit in opposite directions, its outer movement being limited by the tooth projecting from the end of the 60 ratchet teeth thereon coming in contact with the shoulder upon the handle, thus preventing the jaw from being fully removed from the slot. By swinging the handle to its outer limit, the jaw may be moved to any 65 adjusted position desired without interference between the teeth of the ratchet bar and those upon the lever. When it is desired to compress the jaws against an object, the movable lever may be swung toward the 70 lever of the fixed jaw and the jaws will be held in clamping relation with the object which they engage.

What I claim to be new is:—

A wrench comprising a fixed jaw with a 75 handle and having a transverse slot therein, a sliding jaw with a straight shank portion at right angles to the inner face of the jaw provided with teeth upon its inner edge, a projection at the end of said shank and ex- 80 tending beyond said teeth, a lever fixed to the handle of the fixed jaw and provided with gear teeth upon the inner end thereof and designed to engage the serrations upon the shank portion of the sliding jaw, and 85 a ratchet tooth upon said lever designed, when the lever is swung outward at right angles to the length of the handle to which it is pivoted, to be positioned in the path of said projection, serving to limit the move- 90 ment of the sliding jaw in one direction and allowing the same to move freely in the opposite direction, as set forth.

In testimony whereof I hereunto affix my signature in the presence of two witnesses. 95

JOHN E. FINNEY.
